UNITED STATES PATENT OFFICE.

EDWARD HETT, OF NEW YORK, N. Y.

PRINTING-PRESS.

SPECIFICATION forming part of Letters Patent No. 637,602, dated November 21, 1899.

Application filed March 6, 1899. Serial No. 707,921. (No model.)

To all whom it may concern:

Be it known that I, EDWARD HETT, of New York, (New Dorp,) in the county of Richmond and State of New York, have invented a new 5 and useful Improvement in Printing-Presses, of which the following is a specification.

My invention relates to presses, and particularly to lithographic presses. Its object is to construct a press that in one continuous 10 operation will print lithographically in one or more colors and also print typographically advertising or other matter upon a continuous web; also, to provide improved means in presses where a printing-cylinder or printing- 15 cylinders are used for moving such cylinder or cylinders radially outward from or inward toward the press and also improved means for removing them from the press or placing them in position in it, particularly in presses 20 where there are a plurality of printing-cylinders; also, to provide improved means for moving the printing-cylinder and impression-cylinder of a press toward or away from each other, and for thus properly timing the printing 25 and regulating the pressure between the cylinders, and also to provide improved means for spreading or distributing the ink upon the surface of the ink-distributing roller.

I have shown in the drawings, in which 30 similar reference characters in the different figures refer to corresponding parts, and will now proceed to describe the preferred form of my improved devices.

Figure 1 is a side elevation of a press embodying my invention. Fig. 2 is a vertical longitudinal section, taken on the lines 2 2 in Fig. 3, looking in the direction of the arrow; and Fig. 3 is a vertical cross-section, taken on the line 3 3 in Fig. 1, looking in the direction 40 of the arrow. Fig. 4 is a side elevation of one form of standard for holding printing-cylinders preparatory to their introduction into the press or their removal therefrom. Fig. 5 is a side elevation of another form of stand- 45 ard arranged, as shown, for use in a press having six printing-cylinders. Fig. 6 is an end view of the same, showing a printing-tube in position upon one of the receiving-arms. Fig. 7 is a vertical cross-section of the 50 same. Fig. 8 is a detail of one of the swinging heads; and Figs. 9 and 10 are horizontal

cross-sections on the lines 9 9 and 10 10 of Fig. 7, respectively.

My improved devices are shown in the drawings in connection with a multicolor 55 lithographic press in which the impression-cylinder is a large drum and the printing-surfaces are hollow cylindrical printing-tubes mounted upon more substantial but hollow form-cylinders, the latter being mounted upon 60 permanent shafts of the press and arranged around the periphery of the drum, although my improved devices may be used with other kinds of presses.

1 represents the framework of the press, 2 65 the drum, and 3 the web. The web passes from roll 4 around rollers 5 5, thence around the periphery of the drum, and thence between delivery-tapes 7 and 8, the former mounted on rollers 9 and the latter on wheels 70 10, the web being cut into sheets by cutter-cylinders 6 and 10 and delivered in any usual manner. As the cutting and delivery devices form no part of my invention, they are not shown in detail and will not be further de- 75 scribed.

11 11 are two lithographic-printing cylinders arranged to make contact with the periphery of the drum, each consisting, preferably, of an outer hollow shell or tube 12, hereinafter spoken of as the "printing-tube," having a cylindrical lithographic surface mounted upon a more substantial but hollow form-cylinder 13, the latter mounted upon a shaft 14 of the press, which shaft will hereinafter be 85 referred to as the "permanent" shaft of the form-cylinder. 14^a is a typographic cylinder also arranged to make contact with the periphery of the drum and adapted to print upon the web advertising or other matter. 90 It is preferably similarly constructed of a permanent shaft, form-cylinder, and printing-tube.

15 15 15 are frames carrying the inking-rollers, including the ink-distributing rollers 95 16 16 16. They and the inking mechanism may be of any ordinary construction, although preferably these frames are constructed as shown and described in my application for a patent, Serial No. 593,796, filed June 1, 1896, 100 and are adapted to swing outward out of the way of the printing-cylinder, so as to permit

of its radial removal from the press, as will presently be described. The rollers 17 17 convey ink from the ink-distributing rollers 16 16 to the printing-cylinders 11 11. Rollers 18 are additional rollers arranged to make contact with the surface of ink-distributing rollers 16 in order to spread the ink upon that cylinder more evenly and smoothly, and thus aid the ink-conveying rollers 17 17 in their work and cause them to carry and apply the ink more regularly and evenly to the surface of the printing-cylinder. These rollers 18 will hereinafter be spoken of as "ink-spreading" rollers. 19 19 are ink-fountains, 20 20 ink-fountain rollers, and 21 21 reciprocating ink-fountain rollers for conveying ink from the ink-fountain rollers to the ink-distributing rollers. 22 22 are water-fountains, 23 23 the water-fountain rollers, and 24 24 reciprocating rollers for conveying water from the water-fountain rollers to the water-rollers 25 25, the latter conveying it to the printing-cylinder. All these and other parts of the inking and dampening mechanism may be of any suitable construction and will not be further described, as, with the exception of the ink-spreading rollers 18 18, none of them form any part of my invention.

The number of lithographic cylinders 11 30 may be varied at will, depending upon the number of colors to be printed upon the web. By means of my improved press a plurality of lithographic impressions in different colors and an impression from a typographic surface of advertising or other printed matter can be made simultaneously and in the same continuous operation upon the same side of a continuous web, thus effecting a great saving in time in the amount and character of machinery required and in expense.

Heretofore in presses in which printing-cylinders have been arranged around the periphery of a larger impression cylinder or drum it has been usual in removing such printing-cylinders from the press or in placing them in position thereon to move them outward from or inward toward the drum by means of arms secured to overhead supports or supports outside of or surrounding the press. Such devices occupy considerable space, are more or less cumbersome, and are clumsy in operation. By my improved devices printing-cylinders or form-cylinders and their permanent shafts and the printing-tubes thereon are moved radially outward or inward from or toward the center of the press by mechanism which lies toward the center of the press or within the circle of the form-cylinders. My improved devices for this purpose occupy much less room than those heretofore in use, are simple and compact in construction, and are operated more easily and with greater precision. They consist, broadly, of arms mounted centrally in the press and adapted to move radially to engage with the shafts of the printing-cylinders and to move them radially outward or inward

from or toward the center of the press or the impression-drum to enable the printing-cylinders to be removed from the press or to be placed in position therein and suitable means for moving said arms radially, such means being preferably driven by the driving mechanism of the press. These devices in their preferred form are as follows:

26 26 are radial arms, two for the shaft of each printing-cylinder, tube, or form-cylinder, screw-threaded for the greater part of their length and fitted within interiorly-screw-threaded nut-sleeves 27 27. Each nut-sleeve 80 is loosely mounted in a bearing 28^a, carried by a bracket secured to the framework of the press. Each nut-sleeve 27 carries at its lower end a beveled gear-wheel 29, which meshes with a large beveled gear-wheel 30. Nut-sleeve 27 can rotate freely in either direction in bearing 28^a and is held in place in the bracket by collar 28 and shoulder 31 and is prevented from lengthwise movement in its bearing. Radial arms 26 have at their upper ends bearings 32 32, adapted at the proper time to carry permanent shaft 14, as will be hereinafter described. One of each set of radial arms has preferably some locking device for securing the permanent shaft to these 95 bearings. This may be of any suitable construction. In the drawings it is shown as a locking-arm 33, connected with the radial arm and adapted to be moved to be out of the way of the form-cylinder and printing-tube when they are being removed from or placed upon permanent shaft 14, as hereinafter described. In the form shown in the drawings the locking-arm 33 is shown as consisting of the upper part of radial arm 27 and a loose piece 100 115, carrying bearing 32. This loose piece is cylindrical at its lower end and forked at its upper end, the forks being adapted to take around shaft 14.

116 is a ring which is adapted to slip up 110 and down on arm 33 and be locked to arm 33 by means of tightening-screws 117. When the parts are in position in the press, ring 116 surrounds the upper end of 33 and the lower end of 115 and is clamped to both of them by 115 screws 117. When it is desired to remove the printing-tube, screws 117 are unscrewed and ring 116 slipped down until it clears the lower end of piece 115. The piece 115 can then be slipped to the side and removed. The printing-tube can then be taken off.

Gear-wheels 30 are driven by bevel gear-wheels 34 upon shafts 35. Shafts 35 carry at their other end bevel gear-wheels 36, which mesh with bevel-gears 37 upon shaft 38. The 125 latter shaft has at one end a bevel-gear 39 meshing with bevel-gear 40 upon shaft 41. The latter shaft may be turned in any suitable way by hand or by power.

When it is desired to remove a printing-cylinder or a printing-tube or form-cylinder from the press, shaft 41 is turned in one direction, thus rotating gear-wheels 30 and nut-shafts 27 in one direction. As nut-shafts

27 are radially immovable, radial arms 26, through the action of the screw-threads, are moved radially outward from the press, bearings 32 are brought into contact with permanent shaft 14 and carry it and the form-cylinder and printing-tube radially outward until the permanent shaft 14 comes into line with receiving-shaft 42 upon standard 43.

In the above-described mechanism for moving the permanent shafts of the printing-cylinders outward from or inward toward the center of the press I have shown as my preferred form a screw and nut engaging with each other, one part being movable radially and the other stationary and being actuated by the driving mechanism of the press. Any suitable means may of course be employed for imparting radial motion to the radial arms, and any suitable devices for actuating said means may be employed without departing from my broad invention. For example, the screw and nut might be dispensed with, other suitable mechanism for imparting radial motion being substituted in their place, or where a screw and nut are employed for the purpose it is not essential that the screw be the movable member and the nut the immovable one or that the screw be the member connected to the radial arms.

30 Any suitable devices for removing a printing-cylinder from the radial arms or of placing it thereon or of removing a printing-tube and form-cylinder from the permanent shaft or of placing them thereon may be employed; 35 but where hollow removable printing-tubes and removable form-supporting cylinders are used I prefer to use a standard for supporting the printing-tubes or form-cylinders, or both, after they have been removed from the 40 permanent shafts of the press or before they are about to be placed upon them. This standard has a plurality of receiving-shafts, preferably one for each printing-cylinder of the press, each receiving-shaft being mounted 45 in the standard so as to swing horizontally to bring the shaft into the proper position for removing a printing-tube or form-cylinder therefrom to a permanent shaft of the press or for removing a printing-tube or form-cylinder 50 from a permanent shaft of the press to the receiving-shaft. These standards may be fitted with any number of receiving-shafts, and they may be arranged upon the standard in any suitable manner to meet the requirements 55 of presses having a different number of printing-cylinders or printing-cylinders differently arranged. In Fig. 4 I have shown a form of standard adapted to a press having three printing-cylinders and in Fig. 5 a form 60 of standard adapted to a press having six printing-cylinders. In the form of standard shown in Fig. 4 the receiving-shafts are not movable vertically, whereas in the form shown in Fig. 5—the preferred form—the receiving-shafts, or some of them, are vertically movable to aid in the placing of printing-tubes or form-cylinders upon the receiving-shafts

or in the removing of them therefrom. In the form shown in Fig. 4 the receiving-shafts are arranged in the arc of a circle, so that 70 when the permanent shafts are moved outward radially to their limit each receiving-shaft will register with its corresponding permanent shaft. In the form shown in Fig. 5 some of the receiving-shafts are raised vertically before they can be brought into the proper position to register with their corresponding permanent shafts of the press, the form of standard shown in Figs. 5 to 10, inclusive, being described at length farther on 80 in this specification.

Referring now to the form shown in Fig. 4, each receiving-shaft is secured in a swinging head 44, connected with standard 43 by a swivel-joint 45, so that it can be swung around. 85 A sliding bolt 46 in the end of receiving-shaft 42 is adapted to take into a hole 47 in the end of the permanent shaft, by means of which the two shafts may be made into one composite shaft, whereupon form-cylinder 13 or 90 printing-tube 12, or both, can be slipped along the composite shaft, locking-arm 33 having first been swung out of the way, until they rest wholly upon receiving-shaft 42. The two shafts are then disconnected. Receiving- 95 shaft 42 and its head 44 are then swung around, when the printing-tube or form-cylinder can be removed therefrom.

When a printing-tube alone is removed, a tube-holder 48, composed of a hollow shaft 100 and of shoulders 49, is first slipped upon receiving-shaft 42 and the printing-tube is slipped along from the form-cylinder onto shoulders 49. In Fig. 3 one of the receiving-shafts is shown as carrying a tube-holder, 105 (represented in dotted lines,) while in Fig. 4 it carries a form-cylinder and printing-tube. Printing - cylinders or printing - tubes and form-cylinders are placed in position in the press in the same way, the steps being taken, 110 of course, in the reverse order.

Motion is imparted to drum 2 through belt 50, pulley-wheel 51, shaft 52, and pinion 53, meshing with spur-wheel 54 upon shaft 54^a. A pinion 54^b upon the other end of shaft 54^a 115 meshes with gear 54^c upon the inside of the drum, thus rotating the latter. Spur-wheel 55 upon drum 2 meshes in cog-wheel 56 upon shaft 14, thus rotating printing-cylinder 11. Spur - wheel 57, also upon drum 2, meshes 120 with pinion 58, the latter meshing with cog-wheel 59 upon the shaft of ink-distributing roller 16, thus driving the latter roller. The other inking-rollers and mechanism and dampening-rollers and mechanism are driven and 125 operated in any usual manner, and as such driving mechanism forms no part of my present invention it will not be further described.

My improved devices for causing the various printing-cylinders to approach and make 130 contact with the drum to effect the lithographic or printing and to recede therefrom and to take these steps in their proper order and time and also for regulating the pressure

between the cylinders and drum when in contact will now be described.

In their usual position in the press permanent shafts 14, carrying the form-cylinders and printing-tubes, rest upon bearings in movable supports 60. These supports are carried by rods 61 61, the latter being capable of vertical movement. This motion is imparted to them through a projection from or 5 a connection of the rods 61 bearing against eccentrics 62 62, mounted upon the shaft 63. In the drawings this connection is shown as a ring 63^a, pivoted to the lower end of rods 61 61, encircling the eccentrics. Shaft 63 is 10 shown as having at each end three eccentrics, one for each permanent shaft of the form-cylinders. Motion is imparted to shaft 63 by the following-described mechanism: A spur-wheel 64 on shaft 63 meshes with pinion 65 15 on shaft 66. This shaft also carries bevel gear-wheel 67, which meshes with bevel-gear 68 on shaft 69. The latter shaft is turned in any suitable manner. As shaft 63 rotates arms 61 rise and fall, and thus, through movable supports and bearings 60 60, raise and 20 lower the permanent shafts and move the printing-tubes into or out of contact with drum 2. By properly arranging the form and position of the eccentrics these movements of the various parts can be correctly 25 timed.

Rods 61 are screw-threaded near their upper ends and carry nuts 70, by means of which the movable supports and bearings can be 30 adjusted upon rods 61, and the degree of pressure between the printing-tube 12 and drum 2 can thus be readily and accurately regulated.

The mechanism for moving the inking 35 mechanism into or out of operative position is as follows:

71 is a shaft carrying at one end a bevel-gear 72. This shaft is turned in any suitable manner, as by hand. Gear 72 meshes 40 with bevel-gear 73 on shaft 74, the latter shaft having at its other end bevel-gear 75, which meshes with a large bevel gear-wheel 76. Bevel-gear 77 on shaft 78 also meshes with gear-wheel 76. Shaft 78 has at its other end 45 a worm 79, which engages with worm-wheel 80, mounted on shaft 81, which carries inking-frame 15. As shaft 71 is rotated one way or the other the inking-frame 15 is raised or lowered, carrying the inking-rollers out of or 50 into operative position.

Referring now to the form of standard illustrated in Figs. 5 to 10, inclusive, 42 are the receiving-shafts, which in this case are shown as six in number, and are adapted to be 55 used and to register with the printing-cylinders of a six-color-printing press, for example. Each receiving-shaft is mounted in a swinging head 44, so as to be capable of horizontal movement. Two of the swinging heads—the lower two—are mounted upon stationary bases 82 82, firmly secured to standard 43. These swinging heads and their re-

ceiving-shafts are capable of simply one movement—namely, a horizontal swinging motion. The other swinging heads and their 70 receiving-shafts are mounted upon brackets 83, these brackets being adapted to move vertically upon a post 84, secured to and forming part of standard 43. As shown, each of the brackets carries two of the swinging heads 75 with their receiving-shafts—namely, one at each end. A vertical movement is imparted to brackets 83 up and down the post 84 by mechanism presently to be described. By these means the receiving-shafts mounted on 80 the brackets can be brought down to the same or substantially the same level as the lower receiving-shafts, printing-tubes or form-cylinders can be readily placed thereon, and the four receiving-shafts can then be raised to 85 their proper height, the receiving-shafts be swung into register with the permanent shafts of the press, and the printing-tubes or form-cylinders be easily removed, or the reverse operation may take place. In the latter case 90 the printing-tubes or form-cylinders after having been placed upon the receiving-shafts can be easily brought down to a level where they can be readily handled. In the preferred form I have shown the means for moving the 95 brackets vertically as driven by the driving mechanism of the press, and these means are so constructed that the upper bracket will move downward or upward at substantially twice the speed of the middle bracket, so that 100 both brackets will bring the receiving-shafts to the lowest level at about the same time, or will raise them to the proper height at the same time.

The means for imparting vertical motion to 105 the brackets consists of the following devices: The post 84 is composed of two pieces, each of which forms part of a hollow cylinder, each piece being securely fastened to the base of the post and being secured together at the 110 top by cap 88, screw-threaded on its interior and screwed over the upper part of the two pieces 84, which are at this point screw-threaded on their exteriors, as shown at 89, Fig. 7, a space 85 being left between the corresponding edges of each piece of post 84 on each side of the post. In the center of the post runs a screw-threaded shaft 86, mounted in bearings 87, secured to the base of post 84 and bearing 90, forming part of cap 88. 91 115 is a nut encircling shaft 86 inside of the two pieces forming post 84 and is free to move upward and downward upon the screw of shaft 86. Each bracket 83 is provided with 120 a nut 91. Each nut 91 has a ring 92, which encircles post 84 and is connected to the nut proper, 91, by two arms 93, which project 125 through the openings 85. The parts 91, 92, and 93 may be cast in one piece or be secured together in any suitable way. These parts 130 are secured to brackets 83 by bolts 94. Whenever screw-threaded shaft 86 is rotated, each nut 91, and with it its corresponding bracket 83, will be raised or lowered, depending upon

the direction of rotation of shaft 86. I prefer to drive shaft 86 through the driving mechanism of the press and preferably through a controlling-engine, so that the movement of the brackets can be easily and accurately controlled. As shown, shaft 86 is driven by means of a beveled gear 95 at its end meshing with a beveled gear-wheel 96 on shaft 97, the latter communicating with any suitable source of power, preferably a controlling-engine, such as is shown and described in one of my earlier applications. As this, however, forms no part of my present invention, the details are not shown and will not be further described.

In order to impart a more rapid motion to the upper bracket 83 than that given to the lower bracket, I have given a steeper pitch, as illustrated at 98, to the part of the screw 20 of shaft 86 traversed by the nut of the upper bracket than is given to the screw of the lower part of the shaft, as illustrated at 99, which part of the screw-threaded shaft is traversed by the nut of the lower bracket. By these 25 means I am enabled to lower or raise both brackets in the same time.

In Fig. 8 I have shown my present way of mounting a swinging head in the brackets or the bases or supports for such swinging heads. 30 100 represents the cylindrical opening in the top of the swinging head, adapted to receive the receiving-shaft 42, which shaft is secured in place therein in any suitable manner. 101 represents the part of the bracket 83 or the 35 base 82 upon which the swinging head rests and turns. This part 101 is provided on its upper face with circular plate 102, made of hardened steel and secured to part 101 by screws 103. A ring 104, preferably of hardened steel, is fastened to the under face of the swinging head by screws 105. This ring projects inward toward part 101 under plate 102, thus securing the swinging head in position. By means of this mechanism the 40 swinging head is free to swing and at the same time is securely held in place upon its base or support.

If desired, automatic means may be employed for turning off the power which drives shaft 86 when the brackets have reached their upward position or their lower position. In Figs. 5, 6, and 7 I have illustrated the presence of such devices. Thus for the purpose of automatically stopping the brackets at 50 their upper limit of motion I provide two contact-points 106 and 107, 106 being fastened to although insulated from the upper bracket and being connected by wire 108 with a battery or other source of electricity and contact-point 107 being secured to the upper part 55 of post 84 and being connected by wire 109 to the other pole of the battery or source of electricity, so that when contact-points 106 and 107 make contact, as they will when the brackets have reached their upward limit of motion, a circuit will be closed through some suitable source of electricity and the power

be shut off which drives shaft 97. The mechanism and manner of thus shutting off the power are not shown in the present application, as they form no part of my present invention, having been described in a previous application of mine. Contact-point 107 is mounted upon a circular ring 110, screwed upon the upper part of post 84. In the same 70 way power can be automatically shut off from shaft 86 when the brackets reach their lowest point by means of contact-point 111, secured to and insulated from the lower bracket, its wire 112 connecting with the battery or source 75 of electricity and contact-point 113, secured to the base of post 84, and its wire 114 connecting with the opposite pole of the battery or source of electricity.

My invention has been shown in connection 80 with a press in which the printing-cylinders are each composed of a hollow printing-tube mounted upon a more substantial but hollow form-cylinder, the latter being mounted upon a shaft referred to herein as a "permanent" 90 shaft, the printing-tube being removable from the form-cylinder and the latter being removable from the permanent shaft. It may be used, however, in all its features, except the receiving-standard, with printing-cylinders 95 that are constructed in other ways than that above described—as, for example, with solid printing-cylinders.

What I claim as new, and desire to secure by Letters Patent, is—

1. The combination in a press, of a printing-cylinder, a shaft upon which it is mounted, arms mounted centrally in the press and adapted to move radially to engage with the shaft of the printing-cylinder and to move 105 the latter radially outward to disengage the cylinder from the frame of the press to enable the printing-cylinder to be removed from the press or to be placed in position therein, and means for moving said arms radially, 110 substantially as set forth.

2. The combination in a press, of a printing-cylinder, a shaft upon which it is mounted, arms mounted centrally in the press and adapted to move radially to engage with the 115 shaft of the printing-cylinder and to move the latter radially outward to disengage the cylinder from the frame of the press to enable the printing-cylinder to be removed from the press or to be placed in position therein, 120 and means for moving said arms radially, and means for removing the printing-cylinder from the arms or of placing it thereon, substantially as set forth.

3. The combination with a form-cylinder 125 and its permanent shaft adapted to carry a lithographic or printing-tube, of arms mounted radially in the press adapted when raised or lowered to move the permanent shaft and cylinder radially outward to disengage the 130 cylinder from the frame of the press to enable the form-cylinder or a printing-tube mounted thereon to be removed from the press or be placed in position therein, and means for

radially moving said arms, substantially as set forth.

4. The combination with a form-cylinder and its permanent shaft adapted to carry a lithographic or printing tube, of arms, mounted radially in the press, adapted, when raised or lowered, to move the permanent shaft and cylinder radially outward to disengage the cylinder from the frame of the press to enable 10 the form-cylinder or a printing-tube, mounted thereon, to be removed from the press or be placed in position therein, means for radially moving said arms, and means for removing the printing-tube or form-cylinder from 15 the permanent shaft or of placing it thereon, substantially as set forth.

5. The combination with a form-cylinder and its permanent shaft adapted to carry a lithographic or printing tube, of arms, mounted 20 radially in the press, adapted, when raised or lowered, to move the permanent shaft and cylinder radially outward from or inward toward the press to enable the form-cylinder or a printing-tube, mounted thereon, to be removed from the press or be placed in position therein, bearings on said arms to receive and hold the permanent shaft of the form-cylinder and locking-arms, forming one 25 of said bearings, adapted to be moved out of 30 the way of the form-cylinder and printing-tube to permit of their removal from or insertion into the press, and means for radially moving said arms, substantially as set forth.

6. The combination with a form-cylinder and its permanent shaft adapted to carry a lithographic or printing tube, of arms, mounted radially in the press, adapted, when raised or lowered, to move the permanent shaft and cylinder radially outward from or inward toward the press to enable the form-cylinder or a printing-tube, mounted thereon, to be removed from the press or be placed in position therein, bearings on said arms to receive and hold the permanent shaft of the form-cylinder, locking-arms, forming one of 40 said bearings, adapted to be moved out of the way of the form-cylinder and printing-tube to permit of their removal from or insertion in the press, means for radially moving said 45 arms, a standard having a receiving-shaft, adapted to receive and support the form-cylinder or printing-tube, and means for connecting said shaft and the permanent shaft of the form-cylinder so as to form one continuous shaft, whereby the printing-tube or form-cylinder may be slipped from one shaft to the other and may be removed from or placed in, the press, substantially as set forth.

7. The combination with a printing-cylinder and its shaft, of arms, mounted radially in the press, adapted, when raised or lowered, to move the shaft and cylinder radially outward from or inward toward the press, screw-threads on said arms, a nut-sleeve surrounding each of said arms, mounted in a sleeve, fixedly secured to the framework of the press, and adapted to freely rotate with-

in said sleeve and provided with interior screw-threads, a gear-wheel on each of said nut-sleeves and gearing connecting said gear-wheels with a source of power, whereby, when the power is applied in one direction, the arms will raise the shaft of the printing-cylinder and, when applied in the other direction, they will lower it so as to permit the removal from or placing in the press of the printing-cylinder, substantially as set forth.

8. The combination with a form-cylinder and its permanent shaft adapted to carry a lithographic or printing tube, of arms, mounted radially in the press, adapted, when raised or lowered, to move the permanent shaft and cylinder radially outward from or inward toward the press, bearings on said arms to receive and hold the permanent shaft of the form-cylinder, locking-arms, forming one of said bearings, adapted to swing out of the way of the form-cylinder and printing-tube to permit of their removal from or insertion into the press, screw-threads on said arms, a nut-sleeve surrounding each of said arms, itself mounted in a sleeve fixedly secured to the framework of the press and adapted to freely rotate within said sleeve and provided with interior screw-threads, a gear-wheel on each of said nut-sleeves and gearing connecting said gear-wheels with a source of power, whereby, when the power is applied in one direction, the arms will raise the permanent shaft of the form-cylinder and, when applied in the other direction, they will lower it so as to permit the removal from or placing in the press of the form-cylinder or printing-tube, substantially as set forth.

9. The combination with a form-cylinder and its permanent shaft adapted to carry a lithographic or printing tube, of arms, mounted centrally in the press, adapted, when raised or lowered, to move the permanent shaft and cylinder radially outward from or inward toward the press, bearings on said arms to receive and hold the permanent shaft of the form-cylinder, locking-arms forming one of said bearings adapted to swing out of the way of the form-cylinder and printing-tube to permit of their removal from or insertion into the press, screw-threads on said arms, a nut-sleeve surrounding each of said arms, mounted in a sleeve fixedly secured to the framework of the press and adapted to freely rotate within said sleeve and provided with interior screw-threads, a gear-wheel on each of said nut-sleeves, gearing connecting said gear-wheels with a source of power, whereby, when the power is applied in one direction, the arms will raise the permanent shaft of the form-cylinder, and, when applied in the other direction, they will lower it so as to permit the removal from or placing in, the press, of the form-cylinder or printing-tube, a standard having a receiving-shaft, adapted to receive and support the form-cylinder or printing-tube and means for connecting said shaft and the permanent shaft of the form-cylinder.

so as to form one continuous shaft, whereby the printing-tube or form-cylinder may be slipped from one shaft to the other and may be removed from or placed in, the press, substantially as set forth.

10. In combination with a press having a plurality of printing-cylinders arranged radially around a drum, a standard, swinging heads secured to the standard by swivel-joints, and a plurality of receiving-shafts secured to said swinging heads and adapted to receive and support form-cylinders or printing-tubes, whereby the form-cylinders or printing-tubes may readily and simultaneously be removed from or be placed upon, the permanent shafts of the printing-cylinders, substantially as set forth.

11. In combination with a press having a plurality of printing-cylinders arranged radially around a drum, a standard, having a plurality of receiving-shafts arranged in the arc of a circle and adapted to register with the permanent shafts of the printing-cylinders and means for connecting the receiving-shafts with the permanent shafts, whereby the form-cylinders or printing-tubes may readily and simultaneously be removed from or be placed upon, the permanent shafts of the printing-cylinders, substantially as set forth.

12. The combination in a press of a series of printing-cylinders, shafts upon which they are mounted, a series of sets of arms mounted centrally in the press, each set of arms being adapted to move radially to engage with the shaft of one of the printing-cylinders and to move the latter radially outward from or inward toward the press, to enable the printing-cylinder to be removed from the press or to be placed in position therein, and means, actuated by the driving mechanism of the press, for simultaneously moving the said series of sets of arms radially, substantially as set forth.

13. The combination in a press of a series of printing-cylinders, shafts upon which they are mounted, a series of sets of arms mounted centrally in the press, each set of arms being adapted to move radially to engage with the shaft of one of the printing-cylinders and to move the latter radially outward from or inward toward the press, to enable the printing-cylinder to be removed from the press or to be placed in position therein, means, actuated by the driving mechanism of the press, for simultaneously moving the said series of sets of arms radially, and means for removing the printing-cylinders from the radial arms or of placing them thereon, substantially as set forth.

14. In combination with a press having a plurality of printing-cylinders, a standard, swinging heads secured to the standard and adapted to swing thereon, and a plurality of receiving-shafts secured to said swinging heads, and adapted to register with the permanent shafts of the printing-cylinders and

to receive and support form-cylinders or printing-tubes, whereby the form-cylinders or printing-tubes may readily and simultaneously be removed from or be placed upon the permanent shafts of the printing-cylinders, substantially as set forth.

15. In combination with a press having a plurality of printing-cylinders, a standard, swinging heads secured to the standard and adapted to swing thereon, a plurality of receiving-shafts secured to said swinging heads and adapted to register with the permanent shafts of the printing-cylinders and to receive and support the form-cylinders or printing-tubes, and means for connecting the receiving-shafts with the permanent shafts, whereby the form-cylinders or printing-tubes may readily and simultaneously be removed from or be placed upon the permanent shafts of the printing-cylinders, substantially as set forth.

16. In combination with a press having a plurality of printing-cylinders, a standard, swinging heads secured to the standard and adapted to swing horizontally thereon, and to move vertically thereon, and a plurality of receiving-shafts secured to said swinging heads, and adapted to register with the permanent shafts of the printing-cylinder and to receive and support form-cylinders or printing-tubes, whereby the form-cylinders or printing-tubes may readily and simultaneously be removed from or be placed upon the permanent shafts of the printing-cylinders, substantially as set forth.

17. In combination with a press having a plurality of printing-cylinders, a standard, brackets secured to the standard and movable vertically thereon, means for moving the brackets vertically, swinging heads mounted upon the brackets and adapted to swing horizontally thereon, and a plurality of receiving-shafts, secured to said swinging heads, and adapted to receive and support form-cylinders or printing-tubes, whereby the receiving-shafts may be caused to register with the permanent shafts of the printing-cylinders, and the form-cylinders or printing-tubes may readily and simultaneously be removed from or be placed upon, the permanent shafts of the printing-cylinders, substantially as set forth.

18. In combination with a press having a plurality of printing-cylinders, a standard, brackets secured to the standard and movable vertically thereon, means for moving the brackets vertically, swinging heads mounted upon the brackets and adapted to swing horizontally thereon, a plurality of receiving-shafts secured to said swinging heads and adapted to receive and support form-cylinders or printing-tubes, and means for connecting the receiving-shafts with the permanent shafts, whereby the receiving-shafts may be caused to register with the permanent shafts of the printing-cylinders, and the form-cylinders or printing-tubes may readily and

simultaneously be removed from or be placed upon, the permanent shafts of the printing-cylinders, substantially as set forth.

19. In combination with a press having a plurality of printing-cylinders, a standard, movable brackets secured to the standard and movable vertically thereon, swinging heads mounted upon the brackets and adapted to swing horizontally thereon, a plurality of receiving-shafts secured to said swinging heads, and adapted to receive and support form-cylinders or printing-tubes, a screw-threaded shaft mounted in bearings in the standard and driven by the driving mechanism of the press, nuts meshing with said screw-threaded shaft and secured to the brackets, whereby the brackets will be moved vertically in one direction or the other as the screw-threaded shaft rotates in one direction or the other, and the receiving-shafts may be caused to register with the permanent shafts of the printing-cylinders, substantially as set forth.

20. In combination with a press having a plurality of printing-cylinders, a standard, movable brackets secured to the standard and movable vertically thereon, swinging heads mounted upon the brackets and adapted to swing horizontally thereon, a plurality of receiving-shafts secured to said swinging heads and adapted to receive and support form-cylinders or printing-tubes, a screw-threaded shaft mounted in bearings in the standard and driven by the driving mechanism of the press and having its screw-threads of different pitch upon different parts of the shaft, a nut meshing with said screw-threaded shaft and secured to each bracket, whereby the different brackets will be moved vertically at different rates of speed in one direction or the other as the screw-threaded shaft rotates in one direction or the other, and the receiving-shafts may be caused to register with the permanent shafts of the printing-cylinders, substantially as set forth.

45 21. In combination with a press having a plurality of printing-cylinders arranged radially around a drum, a standard swinging heads secured to the standard and adapted

to swing thereon, a plurality of receiving-shafts, secured to said swinging heads and adapted to register with the permanent shafts of the printing-cylinders and to receive and support the form-cylinders or printing-tubes, and means for connecting the receiving-shafts with the permanent shafts, whereby form-cylinders or printing-tubes may readily and simultaneously be removed from or be placed upon, the permanent shafts of the printing-cylinders, substantially as set forth.

22. In a press, the combination of a printing-cylinder having a printing-tube or form-cylinder and a permanent shaft therefor, a standard, a swinging head secured thereto and adapted to swing horizontally thereon and to move vertically thereon, means for imparting vertical movement to the swinging head, a receiving-shaft secured to the said swinging head, whereby the receiving-shaft may be lowered or raised and may be swung so as to register with the permanent shaft of the printing-cylinder, substantially as set forth.

23. In a press, the combination of a printing-cylinder having a printing-tube or form-cylinder and a permanent shaft therefor, a standard, a bracket mounted thereon adapted to move vertically upon said standard, means for moving the bracket vertically thereon, a swinging head secured to the bracket and adapted to swing horizontally thereon, a receiving-shaft mounted in the swinging head, whereby the receiving-shaft may be lowered or raised and may be caused to register with the permanent shaft of the printing-cylinder and form-cylinders or printing-tubes may easily be removed from or be placed upon the permanent shaft of the printing-cylinder, substantially as set forth.

In testimony whereof I have signed my name to this specification in the presence of two subscribing witnesses.

EDWARD HETT.
